UNITED STATES PATENT OFFICE.

RICHARD TOENNES, OF BOONVILLE, MISSOURI.

TURBINE-ENGINE.

No. 849,942.

Specification of Letters Patent.

Patented April 9, 1907.

Application filed November 7, 1905. Serial No. 286,275.

To all whom it may concern:

Be it known that I, RICHARD TOENNES, a citizen of the United States, residing at Boonville, in the county of Cooper and State of Missouri, have invented new and useful Improvements in Turbine-Engines, of which the following is a specification.

My invention pertains to improvements in what may be termed "turbine-engines." 10 The motive fluid herein employed may be and is preferably oil thrown in a stream or streams upon a turbine-wheel fixed to the engine or driving-shaft by the action of steam exerting or delivering its pressure upon 15 the body of oil or other motive fluid.

The invention has for its object to provide for facility and efficiency in the action of the parts and to carry out these ends in a simple and expeditious manner.

20 Said invention consists of certain structural features substantially as hereinafter fully disclosed and particularly pointed out by the claims.

In the accompanying drawings, illustrating the preferred embodiment of my invention, Figure 1 is a broken perspective view thereof, viewing it generally from the front. Fig. 2 is a side view of the same, disclosing more especially the reversing-lever, &c. 30 Fig. 3 is a vertical section of the engine produced directly in the line of the driving-shaft, the oil-stream-delivering nozzles. Fig. 4 is also a vertical section thereof, taken longitudinally through the steam supply-valves and 35 valve-chest. Fig. 5 is also a vertical section of the same produced transversely through the steam-chest and a steam supply-valve and the live-steam and exhaust-steam ports effective therewith.

40 In practicing my invention I provide a suitable casing or shell 1, having a steam-exhaust outlet 1^b in its top, and preferably superposed with relation to a lower or base chamber 2, whose upper surface or top is 45 formed by the bottom of the former. Within the upper part of the casing or shell 1 is arranged an impact type of turbine-wheel 3, whose shaft 3^a, from which the driving power is taken, is suitably hung or journaled 50 in the lateral walls of the casing or shell 1.

The chamber 2 is subdivided into a number of compartments or subchambers, three being herein shown, 2^a 2^b 2^c, although a greater number may be used, each for holding 55 or receiving a motive liquid, as oil, preferably what is called "cylinder oil," or other

liquid. Said subchambers or compartments are equipped in their upper surfaces with gravity-opening valves 4 to permit the supplying thereof with oil and the draining back thereto of the residue oil for reusing resulting from the oil previously thrown up against the wheel, as will be more fully apparent presently. Said subchambers or compartments are also equipped or furnished 65 with oil or liquid delivering or throwing nozzles 5, arranged below the wheel 3 and about in alinement with a vertical central line passing through the wheel 3. Said nozzles have each oppositely discharging or jetting 70 branches or nozzles proper, 5^a, to deliver the oil or liquid upon the wheel for actuating or causing the turning of the latter in either direction, according to the plane of rotation it may be desired to impart to the power-transmitting shaft, as will be readily understood. 75 To this end also a reversing suitably-apertured rod or plug 6 is also provided, extending through each of the nozzles 5 and having each of its transverse apertures or ports 6^a common to each two ports or passages of the branches 5^a of each nozzle. Said plug or rod is provided with a conveniently-actuated handle or arm 6^b, adapted to be moved back and forth outside of the casing 1 and be suitably retained in either of its two adjusted positions, as in initially delivering the liquid or oil via the nozzles 5, upon the turbine-wheel, or in reversing the delivery action of 80 said nozzles, as is apparent.

Within a steam-chest 7, having a steam-supply-pipe connection or inlet 7^a and arranged upon the chamber 2 at the forward side of the casing or engine, is a number of steam-supply valves 8, equal in number to 95 that of the several oil or liquid chambers 2^a, 2^b, and 2^c and effective for controlling the supply or delivery of steam into the latter upon the contents thereof, but at graduated intervals, to accordingly deliver or discharge 100 the liquid or oil through the nozzles 5 from said chambers upon the wheel, as will be noted from the drawings, for continuously effecting said wheel by the action of said liquid, as is obvious. This graduated delivery action of the steam by the valves is 105 the resultant of eccentrics 9, having their points of connection upon a common shaft 10 in relatively varying radii of said eccentrics, which shaft is suitably mounted, as 110 shown, or otherwise, and which eccentrics are encompassed by rings or collars 11, con-

nected to pitmen 12, in turn connected to said valves. Said valves are adapted to suitably deliver or supply the steam as aforesaid by opening ports 8^a in the top of the steam-chest 7, which steam after having exerted its expansive action upon the oil or liquid in the respective oil or liquid chambers and upon the return movement of said valves which will again cover the ports 8^a will be exhausted from said oil or liquid chambers through additional ports 8^b in the top of the latter, the exhaust-steam escaping through the covered ports 8^a, thus put into communication, by means of ducts 8^c in the valves, with said ports 8^b and entering chambers 8^d and finally passing out through the outlets 1^b. Thus the residue from the oil expelled from the oil-chambers, as indicated, through the nozzles and after having expended its force upon the turbine-wheel will be allowed to reenter said oil-chambers and be reused, as is obvious.

A propelling pawl or dog 13, eccentrically connected, as at 13^a, with the driving-shaft 25 3^a, is effective by engagement with a ratchet-pinion 14, secured to the valve-actuating shaft 10, to provide for imparting the requisite movement to said shaft. These are so related and constructed that the driving-shaft 30 is designed to make about fifty revolutions before the valve-actuating shaft shall make a revolution, thus controlling the action of the steam-supply valves from said driving-shaft for the requisite supply and 35 cut off of the steam in delivering the motive liquid or oil to the turbine-wheel and the refilling of the liquid or oil chambers alternately.

In low-pressure and compressed-air engines water may be used as the motive 40 agent or liquid. Relative variations between the delivering capacity of the oil or liquid nozzles and the diameter of the ratchet-pinion of the valve-actuating shaft

provide for accordingly varying the driving power of the engine. It is noted that by the employment of oil in particular as the motive liquid or medium, having great density or specific gravity, the impact therebetween and the wheel-blades will be greatly increased 45 over that of the action of steam-pressure thereon, comparably about twenty to thirty per cent. greater, as I have found by practical experience. Also it is remarked that in lieu of the use of a slide-valve a rotary valve 50 may be used for effecting the same purpose as obtained thereby. Further, it is observed that the delivery-passages or apertures of the nozzles 5^a may be laterally elongated, which would provide for throwing or 55 ejecting the oil or liquid to a greater advantage upon the wheel-perimeter, it is thought.

I claim—

An engine or apparatus of the character 65 described, comprising a turbine-wheel, liquid or oil containing chambers arranged below said wheel, a plurality of nozzled pipes depending within, and effective for the delivery of the contents of said chambers upon said 70 wheel, a ported plug arranged within, and common to all of said nozzled pipes and extending to the outside of the engine-casing, means for actuating said plug, a steam-chest equipped with inlet and exhaust valves, arranged with relation to said chamber, a 75 shaft bearing a number of eccentrics whose points of connection with said shaft are at relatively varying radii of said eccentrics, said eccentrics having pitmen connection 80 with said valves, and means for actuating said latter shaft from the wheel-shaft.

In testimony whereof I affix my signature in presence of two subscribing witnesses.

RICHARD TOENNES.
